FILTERING SYSTEM AND APPARATUS
THEREFOR

Daniel E. Beduhn, Manitowoc, Wis., assignor to Manitowoc Engineering Corporation, Manitowoc, Wis., a corporation of Wisconsin

Filed Jan. 12, 1961, Ser. No. 82,310
7 Claims. (Cl. 210—169)

This invention relates to systems and apparatus for filtering a fluid, and more particularly relates to a system and improved apparatus for filtering and skimming water of a swimming pool and for vacuuming the swimming pool.

It has long been desired to provide a filtering system and apparatus for residential swimming pools which is inexpensive in manufacture, installation and upkeep; economical in operation and maintenance; compact and easily installed either as a portable or permanent installation, and reliable, practical, simple, effective, durable and efficient in operation.

In heretofore known conventional type filtering systems and apparatus for residential type swimming pools it is generally required that the apparatus of the filtering system be permanently installed and in most instances much of the apparatus is underground, somewhat elaborate and complicated which results in an installation that is expensive to manufacture and install since these installations normally require that manholes be dug, underwater drains provided, valves, gauges, steel tanks and the like, be employed to assure the proper operation thereof.

Also, in the known, more conventional type of filtering systems and apparatus it is necessary that some type of filtering additive or powder be used; require that tedious back washing and messy flushing operations be employed, and large water losses and pressure problems occur which make the operation, maintenance and upkeep of such installations complicated, unreliable and expensive.

Also, the known conventional types of filtering systems usually employ apparatus which is rather complex from the operational standpoint and which includes somewhat complicated and elaborate plumbing installations that normally require that the residence owner or pool user be subjected to an educational program in order to be able to understand and operate the filtering system and the apparatus which is employed therein.

It is the primary object of this invention to provide a filtering system and apparatus for residential swimming pools which is economical to manufacture; inexpensive to install, maintain, and operate; compact and easily installed either as a portable or permanent installation, and is simple, durable, reliable, practical, effective and efficient in operation.

A further object of this invention is to provide a system and apparatus for filtering and skimming water of a swimming pool and for vacuuming the pool while in a substantially water-filled condition.

A still further object of this invention is to provide a filtering system for swimming pools and the like which overcomes the above stated disadvantages while having the advantages wherein the apparatus of the filtering system includes a skimmer unit; a filter unit; a pump unit; a vacuum unit; a flexible conduit placing the intake side of the pump unit in communication with the filter unit in a manner which causes water in the swimming pool to first pass through the skimmer unit, to the filter unit and then to the intake side of the pump, and a conduit in communication with the discharge side of the pump for returning the filtered and skimmed water back to the swimming pool with the vacuum unit being operatively associated with the other units and conduits to enable the swimming pool to be vacuumed while in a substantially water-filled condition.

2

An additional object of this invention relates to a skimmer unit for skimming liquids wherein the skimmer unit is provided with a liquid gate structure which is self adjusting to varying liquid levels of a liquid which is being skimmed.

A further additional object of this invention relates to a skimmer unit for skimming liquids wherein the skimmer unit automatically effects a high velocity current flow on the surface of the liquid being skimmed.

It is also an additional object of this invention to provide a skimmer unit for skimming liquids wherein the skimmer unit skims in a zone which is only near the liquid level where undesirable matter normally hangs suspended and does not waste effort and decrease efficiency by affecting the deeper liquid levels where the liquid is usually free and clear of such undesirable matter.

Another object of this invention is to provide a filter unit for filtering liquid through a filter medium wherein the filter medium is paper.

Yet another object of this invention is to provide a filter unit wherein the filter medium for filtering impurities from a liquid is removably and replaceably supported within the filtering zone of the filtering unit by a resilient cage-like member.

Still another object of this invention is to provide a vacuum unit for vacuuming swimming pools and the like wherein the vacuum unit is operable to vacuum the swimming pool without necessitating the removal of any substantial amount of water which may be contained therein.

It is a further another object of this invention to provide a vacuum unit for vacuuming swimming pools wherein in the swimming pool may be vacuumed without requiring the removal of the water normally contained therein with a part of the water of the swimming pool being employed as a carrier for conveying the particles which have been vacuumed from the swimming pool.

It is also an object of this invention to provide a skimmer-filter device which may be removably secured to a swimming pool installation at the water level therein or effectively floated on the surface of the water in the swimming pool wherein, in either type of installation, the skimmer-filter device is effective to skim and filter the water contained within the confines of the swimming pool.

It is also a further object of this invention to provide a skimmer-filter device which includes a skimmer unit having an opening therein and a gate movably mounted in the opening for skimming undesirable matter from the swimming pool water and a filter unit having a removable and replaceable filter medium of paper for filtering impurities from the swimming pool water.

It is also a still further object of this invention to provide a skimmer-filter device for swimming pools which includes a skimmer unit and a filter unit separably supported by the skimmer unit wherein the skimmer unit is provided with a housing having an opening therein, a gate that defines a skimming edge positioned in the opening at the water level of the swimming pool and a portion of the housing for collecting the impurities which have been filtered from the water of the swimming pool, and the filter unit is separably supported within the confines of the housing and disposed therein above the impurities collector portion of the housing with the filter unit extending below the water level of the swimming pool.

It is also another object of this invention to provide a skimmer-filter device for swimming pools comprising a skimmer unit including a housing having an opening therein and a gate structure disposed in the opening for skimming the water of the swimming pool, and a filter unit that includes a removable and replaceable filter me-

dium for filtering the water of the swimming pool with the filter unit being separably supported within the housing of the skimmer unit.

An important object of this invention is to provide a filter-vacuum device for swimming pools and the like wherein the water contained therein may be filtered while the swimming pool is being vacuumed.

Another important object of this invention relates to a filter-vacuum device for swimming pools wherein a part of the water of the swimming pool is employed as the conveying agent for removing the particles which have been vacuumed from the swimming pool with the particles and other impurities being filtered therefrom and the water that defines the conveying agent is returned into the swimming pool.

An additional important object of this invention relates to a skimmer-filter-vacuum apparatus for swimming pools which includes a skimmer unit provided with an opening having a gate mounted therein for skimming the swimming pool water, a filter unit having a removable and replaceable paper filter medium for filtering the swimming pool water and a vacuum unit for vacuuming the swimming pool while the water remains therein.

Other objects and important features of the invention will be apparent from a study of the following specification which when taken with the drawing together show, illustrate, describe and disclose a preferred embodiment of the invention together with a modification thereof, and what is now considered to be the best mode of practicing the principles of the invention. Still other or additional embodiments or modifications may be suggested to those having the benefit of the teachings, and such other and additional embodiments or modifications are intended to be reserved especially as they fall within the scope and spirit of the subjoined claims.

In the drawing:

FIGURE 1 is a fragmentary pictorial view of a filtering system installed beside a swimming pool with the apparatus thereof having the improvements according to the present invention embodied therein;

FIGURE 2 is an enlarged isometric view of the skimmer-filter-vacuum apparatus of the filtering system as illustrated in FIG. 1;

FIGURE 3 is an enlarged transverse vertical sectional view of the preferred embodiment of the apparatus illustrated in FIG. 2 as taken along the line 3-3 therein looking in the direction of the arrows;

FIGURE 4 is a longitudinal vertical sectional view taken along the line 4-4 of FIG. 2 looking in the direction of the arrows and illustrating the apparatus shown therein;

FIGURE 5 is an isometric view of the filter-vacuum device with certain portions thereof being broken away to better illustrate same, and

FIGURE 6 is an isometric view of the resilient wire cage-like member employed for removably and replaceably supporting the filter medium within the filter unit of the apparatus.

Attention is now directed to FIG. 1 of the drawing wherein there is illustrated a filtering system 10 for filtering and skimming a liquid 12, such as water, which is retained and confined in a container or receiver such as a swimming pool 14, of the type normally installed at a residence, at a water level 16 with the filtering system 10 also being operable to vacuum the swimming pool 14 without requiring that any substantial amount of the water 12 be removed so that the water level 16 may be maintained during the vacuuming operation at the desired level.

The filtering system 10 includes a skimmer-filter-vacuum apparatus 18 having a skimmer-filter device 20 which is provided with a skimmer unit 22 and a filter unit 24 that is separably supported within the skimmer unit 22; a filter-vacuum device 26 which includes the filter unit 24 of the skimmer-filter device 20 together with a

vacuum unit 28; a pump device 30, illustrated as an electrical pump device having a standard type plug-in outlet connection 32; a first conduit 34, preferably flexible, for placing the skimmer-filter-vacuum apparatus 18 in communication with the intake side of the pump device 30, and a second conduit 36 for placing the discharge side of the pump device 30 in communication with the water 12 which is normally retained within the confines of the swimming pool 14 so that there is in effect a closed skimmer-filter-vacuum circuit defined by the apparatus 18 of the system 10.

In operation, the filtering system 10, when employed to skim and filter the water 12 of the swimming pool 14, the pump device 30 will effectively force or induce the water 12 to flow through a skimming zone at the skimmer unit 22 whereat undesirable particles will be skimmed from the water 12 at the water level 16, with the water 12 then flowing through a filtering zone at the filter unit 24 whereat the impurities contained in the water 12 will be removed therefrom and thereafter the skimmed and filtered water 12 will be returned to the swimming pool 14 through the conduit 34, pump device 30 and the conduit 36.

When it is desired to filter and vacuum the swimming pool 14 without requiring that any substantial part of the water 12 be removed therefrom or without requiring that the water level 16 be substantially lowered, the filter-vacuum device 26 is separated from the skimmer unit 22 and employed to remove particles from the swimming pool 14 with a part of the water 12 being employed as a conveying agent, through the influence of the pump device 30, to convey the particles from the vacuuming zone at the vacuum unit 28 into the filtering zone at the filter unit 24 whereat the particles and the impurities being carried by the water 12 are removed with the water 12 then passing through the conduit 34, the pump device 30 and the conduit 36 back to the swimming pool 14.

Attention is now directed to FIGS. 2, 3 and 4 of the drawing wherein there is illustrated, in more detail, the skimmer-filter-vacuum apparatus 18. It is to be noted that the skimmer unit 22 of the apparatus 18 includes a housing 38 substantially of rectangular configuration and defined by a top portion 40, a bottom portion 42, side portions 44-44, a front portion 46 and a back portion 48.

In the preferred embodiment of the skimmer-filter-vacuum apparatus 18, the bottom portion 42, the front portion 46 and the back portion 48 of the housing 38 are formed from a single integral sheet of material, such as anticorrosive metal, plastic, or the like, that is bent into substantially a J-shape with the front portion 46 being the shorter leg of the J and terminating in an edge portion 50. The side portions 44-44 are also formed from like material which may be any suitable anticorrosive metal, plastic, or the like and are reinforced and joined to the back portion 48, the bottom portion 42 and the front portion 46 of the housing 38 by stiffener strips 52 which are curved laterally to define rounded corners 54 with the strips 52 extending along the front of the housing 38 and terminating in side edges 56-56 which are spaced apart and which define with the edge portion 50 and an edge 58 of the top portion 40 an opening 60 in the front portion 46 of the housing 38.

A floating liquid gate structure 62 is disposed in the opening 60 of the front portion 46 of the housing 38 and the gate structure 62 is formed from suitable flexible material, such as any anticorrosive metal, plastic, or the like, which enables the gate structure 62 to be movably mounted, as illustrated by phantom lines in FIG. 3 of the drawing, within the opening 60 so that the gate structure 62 is self adjusting to varying water levels 16 and floats in the water 12 with an upper edge portion 66 thereof being in spaced relationship to the edge 58 in a manner which defines a skimming edge portion over which the water 12 flows through the opening 60 into the confines of the housing 38 with the skimmer edge portion 66 auto-

matically effecting a high velocity current flow on the surface of the water 12 during the skimming operation. Any suitable wedge or locking mechanism 64, such as the bolt-nut structure, as illustrated, may be employed to secure the gate structure 62 to the housing 38. Since the gate structure 62 is bodily flexible and floatably movably mounted to the housing 38 with the skimmer edge portion 66 being self adjusting to varying water levels 16 the skimmer unit 22 is effective to skim only in a skimmer zone which is near the water level 16 where undesirable matter is normally present and hangs suspended in the water 12 and there is no waste of effort or any decrease in the efficiency of the skimming operation since the skimmer unit 22 does not affect the deeper water levels where the water 12 will normally be free and clear of such undesirable matter.

The floating liquid gate structure 62 is provided with a plurality of sealed compartments 68 which impart sufficient buoyancy to the gate structure 62 to enable the gate structure to be effectively buoyantly floatably supported in the water 12 at the water level 16 thereof, and if necessary the sealed compartments 68 of the gate structure 62 may be increased or decreased in capacity to vary the buoyant effect thereof in accordance with the requirements of the system.

In the preferred embodiment of the invention, as illustrated in FIGS. 2 and 3 of the drawing, there is provided adjustable support structure 70 which removably or releaseably secures the housing 38 to a side wall or apron 72 of the swimming pool 14 so that the floating liquid gate structure 62 will be positioned relative to the water level 16 as described above.

However, it may be desirable that the skimmer-filter-vacuum apparatus 18 be floated at the water level 16 in the water 12 of the swimming pool 14 in order to increase the effective skimming operation of the skimmer unit 22 of the apparatus 18. In order to float the apparatus 18 it is only necessary that the apparatus 18 be removed and separated from the wall or apron 72 of the swimming pool 14 and in this embodiment or modification of the invention, not illustrated, an additional float structure is employed in place of the support structure 70 which effectively floats the skimmer-filter-vacuum apparatus 18 in the water 12 with the sealed compartments 68 of the gate structure 62 being effective to dispose the skimmer edge portion 66 adjacent to the water level 16.

The top portion 40 of the housing 38 is provided with an opening 74 into which there is disposed the filter-vacuum device 26 with the filter-vacuum device 26 being separably and removably supported therein and resting on brackets 76 which are secured to the back portion 43 and side portions 44-44 of the housing 38. It is to be expressly noted that the filter-vacuum device 26 is separably and removably nested within the confines of the housing 38 and by reason of the brackets 76 the filter-vacuum device may be easily removed from within the housing 38 for reasons to be more fully described and disclosed hereinafter.

The filter-vacuum device 26 comprises the filter unit 24 and the vacuum unit 28 which are secured together by suitable structure 78, such as screws, bolts or the like. The filter unit 24 includes a shell 80 formed from any suitable material such as a non-corrosive metal or plastic material with the shell 80 being of sachet-like configuration, i.e., an inverted U shape in transverse section as illustrated in FIGS. 3 and 5 of the drawing, defined by a top portion 82 having depending therefrom end 84 and side 86 wall portions with the side wall portions 86 being disposed in a manner which converge toward the top portion 82 so that the side wall portions 86 are inclined away from each other as they extend from the top portion 82. The end 84 and side 86 wall portions of the shell 80 terminate in an annular enlarged end portion 88 to define an open end 90 for the shell 80. The end portion 88 is provided with a plurality of spaced internally threaded re-

cesses 92, for a purpose to be more fully disclosed and described hereinafter. Inwardly projecting, elongated supporting-spacer ribs 94 are disposed along the inner surface of the side wall portions 86 of the shell 80. The top portion 82 of the shell 80 is provided with a neck portion 96 which defines an opening 98 through the top portion 82 of the shell 80 and to which the first conduit 34 may be connected so that the skimmed and filtered water 12 may pass through the opening 98 and then flow through the first conduit 34 to the intake side of the pump device 30 during the filtering-skimming-vacuuming operation of the system 10.

A filter medium support 100 which is of substantially the same configuration as the shell 80 is received within 15 the confines thereof and supported in spaced relationship thereto by reason of the ribs 94. The filter medium support 100 includes a top portion 102, end wall portions 104 and side wall portions 106 which depend from the top portion 102 with the side wall portions 106 diverging 20 relative to each other. In the preferred embodiment of the invention the top portion 102 and the side wall portions 106 of the filter medium support 100 are constructed from suitable mesh screen such as a non-corrosive metal or plastic cloth while the end wall portions 104 thereof 25 are solid. Since the filter support 100 is supported in engagement with the ribs 94 which project inwardly from the shell 80 there is defined between the filter medium support 100 and the shell 80 a space through which the water 12 passes in its travel from the swimming pool 14 to the 30 first conduit 34.

If desired or necessary other additional filter medium supporting structures of suitable mesh screen may be employed, if necessary, and it is to be understood that the size of the mesh screen may vary according to the requirements or needs of a particular installation or system in which the skimmer-filter-vacuum apparatus 18 is employed. It is believed that the disclosure and description of a single filter medium support 100 will suffice for the purpose of describing and disclosing the features there- 40 of in this invention.

A sheet of filter medium 110, preferably of paper, having a substantially rectangular configuration, is placed in direct contact with the inner surface of the filter medium support 100 and extends entirely over the full area of the filter medium support 100 which is defined 45 by the mesh screen top portion 102 and the mesh screen side wall portions 106 thereof.

In order for the filter medium 110 to be removably retained within the confines of the shell 80 in spaced relationship relative thereto by reason of the ribs 94, 50 with the filter medium 110 covering the mesh screen top 102 and side wall 106 portions of the filter medium support 100, a resilient cage-like member 112, as illustrated in FIG. 6 of the drawing, is provided, which is disposed on the inner side of the filter medium 110 and 55 constantly exerts a pressure force thereagainst to retain the filter medium 110 positioned against the filter medium support 100.

The resilient cage-like member 112 which may be 60 formed of any suitable anticorrosive metal, or plastic material, or the like, and includes a plurality of spaced apart inverted U-shaped members 114 each having a bite portion 116 which extends into depending leg portions 118-118 that are disposed in diverging relationship relative to each other and terminate in end portions 120. Longitudinally extending elongated substantially straight members 122 are connected to the adjacent end portions 120 of the leg portions 118 and a longitudinally extending elongated substantially straight member 124 connects the adjacent bite portions 116 of the U-shaped member 65 114 together.

It should be noted that the members 122 together with the leg portions 118 and bite 116 portions form a continuous bearing-supporting surface which engages the filter medium 110 along the peripheral edge portion 70 75

thereof while the member 120 bears against and supports the filter medium 110 along the central portion thereof. If desired additional U-shaped members 114 may be provided for exerting a bearing-supporting surface for intermediate areas of the filter medium 110. The leg portions 118 correspond substantially in configuration to the inverted U-shape of the shell 80 and the filter medium support 100 but in actual practice the leg portions 118 normally diverge to a greater degree than the shell 80 and the filter medium support 100 in order to create the pressure force, as indicated by the arrows in FIG. 3 of the drawing, which enables the filter media 110 to be retained within the confines of the shell 80 during the operational step of filtering the water 12 either alone or in combination with the operational steps of vacuuming and skimming the water 12.

In the operational position, the members 122 of the filter support 100 rest against an abutment 128 which projects inwardly from adjacent the enlarged end portion 88 of the shell 80 with the filter medium 110 and filter medium support 100 also being interposed between the members 122 and the inner surface of the shell 80 to assure that there will be no relative movement therebetween during the operation of the filtering unit 24.

In order that the filter medium 110 may be easily and quickly removed and replaced between the cage-like member 112 and the filter medium support 100 there is provided a handle which in the preferred embodiment of the invention is in the form of an L-shaped projection 126 on each of the members 124 which extend generally inwardly toward each other and then outwardly away from the bite portions 116 of the cage-like member 112 and terminate beyond the confines thereof whereat the projections 126-126 are easily accessible to an operator's fingers so that the projections 126 may be readily grasped and urged toward each other in a manner which will cause the leg portions 118 and the members 122 to move inwardly toward each other free of the abutment 128, as shown by phantom lines in FIG. 3 of the drawing, which enables the entire cage-like support 100 to be removed from within the confines of the shell 80 since the size of the bite portion 116 of the cage-like member 112 is smaller than the open end 90 of the shell 80. With the cage-like member 112 removed, as described and disclosed above, the used paper filter medium 110 may then be removed and replaced.

The vacuum unit 28 of the filter-vacuum device includes a scrubbing-block or head 130 having an endless annular flange portion 132 which defines an opening 134 therethrough of a size substantially equal to the open end 90 of the shell 80 and larger in area than the area of the bite portion 116 of the cage-like member 112 so that the cage-like member 112 may be passed therethrough. The flange portion 132 of the block 130 is of greater width than the enlarged end portion 88 of the shell 80 and is offset upwardly and extends generally inwardly therefrom relative to the inner surface of the shell 80 and defines the abutment 128. A plurality of spaced apart openings 136 are aligned with the internally threaded recesses 92 in the outwardly projecting portion of the enlarged end portion 88 of the shell 80 in a manner to receive the securing structure 78, to removably secure the head 130 of the vacuum unit 28 to the shell 80 of the filter unit 24.

A series of separate and independent bristles 138 are secured to the head 130, in any suitable known manner, with the bristles 138 being disposed closely adjacent to the opening 134 in the head 130 and extending continuously therearound and projecting therefrom in a direction that is away from the opening 98 in the neck portion 96 of the shell 80.

The vacuum unit 28 further includes a bracket 140 which is secured to the exterior or outer surface of the shell 80 in close proximity and adjacent to the neck portion 96 thereon. The bracket 140 is provided with suit-

able structure 142, such as an internally threaded opening therein or the like, for receiving an elongated rod-like actuator 144, as shown by phantom lines in FIG. 5 of the drawing, which enables the filter-vacuum device 26, on removal thereof from the housing 38 of the skimmer unit 22, to be actuated in a desired manner along the bottom or side walls of the swimming pool 14 with the bristles 138 in contact therewith to remove and vacuum undesirable particles therefrom.

In the vacuuming operation, a part of the water 12 in the swimming pool 14 will be employed as the conveying agent for moving the undesirable particles from the swimming pool 14 into the filtering zone at the filter unit 24 and then through the opening 134, the opening 98, the first conduit 34, the pump device 30, the second conduit 36 and then returned to the swimming pool 14 so that it is not necessary to remove the water 12 from the swimming pool 14 which enables the swimming pool 14 to be vacuumed while being maintained in a substantially water-filled condition.

From the above disclosure and description, it is believed that this invention provides a filtering system and apparatus for swimming pools which is economical to manufacture; inexpensive to install, maintain and operate; compact and easily installed either as a portable or permanent installation, and is simple, durable, reliable, practical, effective and efficient in operation.

While the invention has been described in terms of the preferred embodiment and one modification thereof which it has assumed in practice, the scope of the invention should not be deemed to be limited by the precise embodiment and single modifications herein shown, illustrated, disclosed and described, such other embodiments and modifications being intended to be reserved especially as they fall within the scope of the claims here appended.

I claim as my invention:

1. A system for skimming and filtering a liquid, said system comprising, in combination,
  - a skimmer unit disposed within a container wherein such liquid is confined,
  - said skimmer unit having a housing defining a receptacle,
  - said housing having an opening therein whereat there is disposed structure defining a skimming edge,
  - a filter unit having a shell separably supported by the receptacle of the skimmer unit and removable therefrom through a second opening in said housing,
  - said shell having opposed open end portions one of which is disposed below the skimming edge with another open end portion being disposed thereabove,
  - a filter medium support disposed within said shell intermediate the open end portions thereof,
  - a filter medium supported by said filter medium support,
  - a resilient member for removably maintaining the filter medium in contact with the filter medium support,
  - a pump device, and
  - conduit means placing the intake side of the pump device in communication with the open end portion of the shell that is above the skimming edge and placing in the discharge side of the pump device in communication with such liquid.
2. The system as set forth in claim 1 wherein the opening in the housing is located in a side portion thereof, and the second opening is located in a top portion of the housing.
3. The system as set forth in claim 1 wherein said structure which defines the skimming edge comprises
  - a bodily flexible gate within the opening of the housing, and
  - means for enabling the bodily flexible gate to be self-adjusted to position the skimming edge for varying liquid levels.

4. The system as set forth in claim 1 wherein said structure which defines the skimming edge comprises

a bodily flexible gate structure disposed within the opening of said housing for effecting a high velocity of current flow on the surface of such liquid,

said gate structure having a plurality of closed compartments which enables the gate structure to be self-adjusting to varying liquid levels of such liquid.

5. The system as set forth in claim 1 wherein the resilient member maintains the filter medium in contact with the filter medium support throughout substantially the full extent thereof.

6. The system as set forth in claim 1 wherein said shell and filter medium support are of substantially U-shape in cross-sectional configuration having spaced apart side portions joined by a top portion with the side portions extending in a generally common direction from the top portion and disposed in diverging relationship relative to each other.

7. The system as set forth in claim 1 wherein said container is a swimming pool.
